UNITED STATES PATENT OFFICE.

WILHELM HASSE, OF BERLIN, GERMANY.

MACHINE FOR PRESSING CARBON ELECTRODES.

Application filed January 24, 1925, Serial No. 4,511, and in Germany June 17, 1924.

This invention relates to improvements in a machine for pressing carbon electrodes with pressed-in projecting carbon for electric pocket-lamp batteries and similar mouldings, the punch and ejector arranged perpendicularly above one another being set in up and down motion by means of a known crank driving mechanism or crank-disc and the press-table in stepwise rotary motion by means of a gear ring. Furthermore, the pressing of the electrodes, as soon as the press-table is in its position of rest, by means of the downwardly moving punch, and immediately thereupon a slight lifting of the moulding by means of the ejector underneath, are effected by means of a cam disc. As soon as the press-table is set in rotation, the ejector fitted with pressure rollers is moved upwards by the upward incline of a stationary guiding cam, whereby the ejection is completed. Upon the further rotation of the press-table the ejector is held at a certain height until the finished carbon electrode is removed, before further rotation brings it again to its lowermost position by the decline of the guiding cam.

As soon as the ejector holder with ejector assumes its lowermost position, according to the invention, the moulds are again automatically filled with fresh paste, which is compressed therein by a plunger arranged above the press-table. The machine is not only adapted for pressing small pocket-lamp electrodes, but also large electrodes, it performing about 30 crank strokes per minute, which means a capacity per day of 14000 pieces with ordinary moulds and of 42000 pieces with three-part moulds. The maximum capacity per day hitherto attained by hand working amounted to about 3000 pieces.

The accompanying drawings illustrate the improved machine: Figs. 1 and 2 are respectively a sectional front view and a plan view of the same, while Fig. 3 is a side view thereof in the direction of the arrow in Fig. 1, and, Fig. 4 is a diagram indicating the movement of the paste and showing a plan view of the crank-disc with its accessories, Fig. 4^a being a side view of the latter; Fig. 5 is a plan view of part of the gear ring.

The machine is driven by a pulley 1 and toothed wheels 2, 3 which set the crank *d* in motion. The latter moves the crank-bar *c* with the guide-piece *b* up and down, the

punch holder *p* being fixed on said guide-piece and thus caused to participate in the movement thereof together with the punch *p*. By the bevel gearing *e*, *e*¹ with the tap-pet *t*, the gear ring *g* and the press-table *i* are set in step-wise rotary motion. The middle guide-bearing *k* has a circular guiding cam *l*¹ firmly fixed thereon in such a way that, when the press-table is turned in clockwise direction, the upward incline of said cam begins at a point situated at an angle of about 15° from the middle position *m* of the roller *l* of the ejector framing *v*⁴. At an angle of about 90° from the middle position begins *m* the largest height of the cam which extends through a further angle of about 20°, the cam being then gradually declined through a further angle of about 95°. Before the roller *l* arrives upon the guiding cam *l*¹ it is somewhat lifted with the ejector framing *v*⁴ by the cam *n* and the pivoted part *n*¹ on which it rides and which co-operates with the cam *n* (Fig. 4^a), so that the moulding in the mould is also somewhat lifted toward the ejection opening, whereby it is attained that the strongest initial pressure during the ejection is not to be taken-up by the guiding cam *l*¹ but exerted by the cam *n*.

The ejector holder *v*¹ with roller *l* and ejector *v*² are guided by the pins *v*³ fixed on the press-table.

The operation is as follows:—After the moulds *r* in front of the punch have been continuously provided with a carbon and filled with paste, and as soon as the first filled mould arrives in the middle position *m* beneath the punch or ejector respectively, the pressing of the first carbon electrode takes place by the downward movement of the punch *p*. By an upward movement of the ejector the finished moulding is somewhat lifted from the mould by the ejector, which is firmly arranged on the ejector holder, by means of the cam disc until the roller *l* slides upon the guiding-cam *l*¹ in order to be positively guided as soon as the table is set in motion. The roller holders *v*¹ for the rollers *l* are firmly arranged on the ejector framing *v*⁴ carrying the ejector tools *v*², so that the latter execute the same up and down movement as the rollers along the cam. By this arrangement, a continuous working required for wholesale manufacture is ensured.

According to the invention, the paste is filled in the moulds as follows:—Upon the moulds *r* having passed beyond the two first stripping-off planes *z* their openings are filled with loose paste. In the next position, the filled mould arrives beneath the plunger *a* where the loose paste is compressed to about middle of the mould. During the further step-wise movement of the press-table 10 the moulds with the previously pressed paste pass along the other stripping-off planes *z* and are there again filled with loose paste, so that the paste suffices for a rigid finished product. During the further movement, the 15 moulds pass the point where the workman inserts the carbon into the mould. Then, after some further working strokes the full mould with the carbon passes beneath the punch where the carbon is readily pressed 20 and then removed during the further movement. The press-table *i* is covered by a wooden coating *u* for preventing the paste, which contains certain salts, from coming in contact with the iron of the press-table. 25 The moulds, for instance 18 of them, are fixed on the press-table.

Above the wood coating *a* receiver *w* is firmly arranged on which the paste is stored and from which it is gradually delivered 30 onto the wooden coating. On the latter al-

ways so much paste must be available that the moulds can be filled by the stripping-off planes *z* and the plunger *a*. Said stripping-off planes are so arranged on the stationary receiver *w* that the paste on the 35 press-table is permanently agitated above the openings of the moulds *r* whereby the latter are filled with loose paste. To sufficiently fill the moulds, it is recommendable to compress the paste once or several times. 40 For this purpose, the plunger *a* is provided and adapted to be operated from the driving gear of the machine. The degree of compression of the paste depends upon the compactness of the finished product desired. 45

What I claim, is:

In a machine for pressing carbon electrodes, the combination with a stepwise rotary press-table, open moulds thereon, and 50 stationary stripping-off planes, of an up and down movable plunger arranged above said press-table intermediate said stripping-off planes and adapted to engage from time in said moulds, substantially as and 55 for the purpose set forth.

In testimony whereof I have hereunto set my hand.

WILHELM HASSE.
